UNITED STATES PATENT OFFICE.

HOMER S. ROGERS, OF MILWAUKEE, WISCONSIN, ASSIGNOR TO MILWAUKEE AIR POWER PUMP COMPANY, OF MILWAUKEE, WISCONSIN, A CORPORATION OF WISCONSIN.

PNEUMATIC PUMP.

Application filed February 20, 1922. Serial No. 537,807.

To all whom it may concern:

- Be it known that I, HOMER S. ROGERS, a citizen of the United States, residing at Milwaukee, in the county of Milwaukee and 5 State of Wisconsin, have invented certain new and useful Improvements in Pneumatic Pumps, of which the following is a specification, reference being had to the accompanying drawing, forming a part thereof.
- 10 This invention relates to pneumatic pumps and the object of the invention is to improve the construction and operation of pneumatic pumps in the manner to be hereinafter described and claimed.
- 15 Referring to the drawing which accompanies this specification and forms a part hereof, the figure of the drawing is a vertical section of a pneumatic pump.
- Referring to the drawing, the reference 20 numeral 1 designates a pump chamber which is provided with a water inlet valve 2, a water outlet valve 3, an air admission valve 4, and an air exhaust valve 5. The drawing illustrates the parts in the positions 25 which they occupy when water is being forced from the pump chamber, by compressed air, through the water discharge pipe 6. The air exhaust valve 5 is held against its seat 7 by a spring 8 which is 30 sufficiently powerful to hold the air exhaust valve 5 closed against any air pressure to be used in the pump chamber 1. A bell-crank lever 9 is pivoted to the head 10 of the pump by a pivot 11 and one of its arms 35 is pivoted to the air exhaust valve 5 while its other arm is pivoted to the stem 12 which projects from the plunger 13, as clearly shown by the drawing. The stem 12 may be positioned and guided by a web 14 and 40 a recess 15 in a head or cap 16. The spring 8 is illustrated by the drawing as a spiral spring of the open, or compression, type surrounding the stem 12 and bearing at one end against the web 14 and at its other end 45 against the plunger 13 and exerting sufficient pressure to keep the air exhaust valve 5 closed against the pressure of the air in the pump chamber 1. The spring 8 is compressed to the requisite degree of tension when it is assembled with the parts 50 of the pump with which it coacts and its expansion is limited by the air exhaust valve 5 seating against its seat 7. The spring 8 can be compressed, and the air exhaust valve

5 opened, by a fluid-pressure motor 17, which is illustrated by the drawing as comprising a diaphragm 18 and a head 19, between which is a fluid chamber 20, when the water level in the pump chamber 1 has been lowered to a predetermined level. 55

It should be particularly noted that the plunger 13 does not encounter any obstacle to its continued movement under the influence of the spring 8 towards the right, looking at the drawing, so that the air exhaust 60 valve 5 will be firmly seated even though wear takes place or the valve facing 21 swells or shrinks under different conditions.

The fluid chamber 20 can be placed in communication with the lower part of the pump chamber 1 by a valve 22 which can close or open the lower end of a pipe 23 which communicates with the fluid chamber 20. The valve 22 is carried by a valve lever 24 which is pivoted by a pivot 25 to the lower end of the pipe 23. A float 26 is arranged as a low level float and has a stem 27 projecting through a hole in a guide 28 and another stem 29 projecting through a hole in the valve lever 24. 70 The stem 29 has a head 30 below the valve lever 24 so as to close the valve 22 as the float 26 rises. As the area of the diaphragm 18 and the area of the plunger 13 are greater than the area of the air exhaust port 31, 75 the power of the spring 8 can be readily overcome by the pressure exerted in the fluid pressure motor even though the power of the spring 8 is sufficient to keep the air exhaust valve 5 closed, as will be readily understood from the well-known principles of the pressures of fluids upon surfaces or areas differing in size. The air exhaust valve 5 is illustrated as provided with a stem 32 80 projecting downwardly through a guide 33. Toggle-joint members 34 and 35 are pivoted together by a pivot 36 and the member 34 is pivoted to the stem 32 of the air exhaust valve 5 by a pivot 37, while the member 35 is pivoted to a projection 38 by a pivot 39. The projection 38 is illustrated by the drawing as formed integrally with the head 10 of the pump but this specific construction is immaterial as the only object sought is to support the pivot 39 firmly 90 substantially under the pivot 37. The construction forms a toggle-joint which will hold the air exhaust valve 5 open when the 100 105

pivot 36 is moved into a substantially straight line with the pivots 37 and 39. It is preferred that the pivots 36, 37 and 39 fit a little loosely so that, when the air 5 exhaust valve 5 is lifted, the spring 40 can swing the pivot 36 slightly beyond a line through the pivots 37 and 39 against a stop and thus hold the air exhaust valve 5 open. The stop illustrated by the drawing is the 10 stem 41 which projects from a head 42 which rests against a part of the head 10 of the pump but can be forced away therefrom by any suitable motor mechanism, as for example, the diaphragm 43 of a fluid 15 pressure motor 44. This fluid pressure motor 44 is provided with a fluid chamber 45 to which compressed air can be admitted from a duct 46 by an air valve 47 and from which the compressed air can be ex- 20 hausted through an exhaust port 48 which is controlled by the exhaust valve 49. For simplicity of construction the air valve 47 and the exhaust valve 49 may be formed on a member 50 which is provided with a 25 stem 51 connected to a lever 52. The lever 52 is pivoted by a pivot 53 to the stem 51, and by a pivot 54 to the head 10 of the pump, and by a pivot 55 to a weight-float 56. The weight-float 56 should be heavy 30 enough to keep the air valve 47 closed against the pressure of the compressed air in the duct 46, taking into account the leverage exerted by the lever 52, when the water level in the pump chamber 1 is not 35 high enough to buoy up the float 56, and, at the same time, the float 56 should be light enough so that when it is buoyed up by the water the air valve 47 will be opened and at the same time the exhaust valve 49 40 will be closed so that the pressure of the compressed air in the fluid chamber 45 will budge the diaphragm 43 and move the head 42 and stem 41 to push the pivot 36 of the toggle-joint members 34 and 35 beyond a 45 line through the pivots 37 and 39 so that the spring 8 can close the air exhaust valve 5. A light spring 57 tends to seat the air admission valve 4 and the air admission valve 4 is opened by the spring 8 when 50 the toggle-joint members 34 and 35 contact with the valve stem 58.

The compressed air is conducted from any suitable source of supply by the pipe 59 to the air chamber 60 with which the duct 55 61 communicates. The reference numeral 61 designates an air exhaust pipe through which the exhaust air may be conducted from the exhaust chamber 62 to a point above the surface of the water in which the 60 pump is submerged.

The operation of the pump is as follows. Referring to the drawing, the air exhaust valve 5 is closed and is being held closed by the spring 8. The air admission valve 65 4 is open and is being held open by the

spring 8 and the toggle-joint members 34 and 35. The air valve 47 is closed and the exhaust valve 49 is open and these two valves are being maintained in the positions shown by the drawing by the weight of 70 the weight-float 56. The water inlet valve 2 is closed and is held closed by its weight and by the pressure exerted upon it within the pump chamber 1. The valve 22 is closed and is held closed by the float 26 and the 75 pressure in the pump chamber 1. The pressure of the compressed air on the surface of the water in the pump chamber 1 is forcing the water out through the water discharge pipe 6 and the outflowing water 80 is keeping the water outlet valve 3 open. The several parts occupy the positions shown by the drawing until the water level in the pump chamber 1 has been lowered to the line of flotation of the float 26. 85 With a further lowering of the water level, the float 26 will descend with the lowering water level until the further descent of the float 26 is arrested by the float contacting with the valve lever 24, which is 90 held in its valve closed position on account of the pressure in the pump chamber 1 being higher than the pressure in the pipe 23. As the water level continues to lower, more and more of the float 26 will be left 95 out of water until the weight of the float 26 acting on the valve lever 24 is sufficient to overcome the pressure holding the valve 22 closed. The weight of the float 26 will then open the valve 22 suddenly and water 100 will be forced through the pipe 23 into the fluid chamber 20 of the motor 17 and will force the diaphragm 18, the plunger 13, and the stem 12 to the left, compressing spring 8, rocking the bell-crank lever 9, opening 105 the air exhaust valve 5, and bringing the pivot 36 into line with the pivots 37 and 39. The spring 40 will swing the toggle-joint members 34 and 35 over against the stem 41 with the pivot 36 at the right of 110 a line through the pivots 37 and 39. The air admission valve 4 will close, the air pressure in the pump chamber 1 will be reduced by the exhaust of air therefrom, the water outlet valve 3 will close and the water inlet valve 2 will be opened by the hydraulic pressure outside the pump chamber 115 and water will flow into the pump chamber to refill the same. As water refills the pump chamber, the float 26 will be elevated, lifting the valve lever 24 and closing the valve 22. When the water level has risen in the pump chamber sufficiently to submerge enough of the high level float 56 to rock the lever 52, the air valve 47 will be 120 opened and the exhaust valve 49 will be closed, and the pressure of the compressed air in the fluid chamber 45 will budge the diaphragm 43 and force the head 42 and the stem 41 to the left far enough to move 125 130

the pivot 36 to the left of a line through the pivots 37 and 39 and the spring 8 will expand and move the plunger 13 and stem 12 to the right, rocking the bell-crank lever 9, closing the air exhaust valve 5 and swinging the pivot 36 far enough to the left to open the air admission valve 4. The air pressure is now on the pump and the water inlet valve 2 will close, if it happens to be open, and the water will open the water outlet valve 3 and be discharged through the water discharge pipe 6, as already described. When the water level in the pump chamber has lowered sufficiently the weight-
5 float 56 will descend closing the air valve 47 and opening the exhaust valve 49 so that the air pressure in the fluid chamber 45 will be reduced when the air exhaust valve 5 is again opened.
10 The valve lever 24 is provided with a lip 63 to contact with a stop 64 to limit the downward movement of the valve lever 24 and the valve 22 carried thereby.
15 A bleed hole 65 is provided at the upper part of the fluid chamber 20 to allow air which may separate from the water to escape and some water may also escape through this bleed hole, the only point to be observed being that the bleed hole should

20 not be so large as compared with the area of the pipe 23 as to materially reduce the pressure in the fluid chamber 20 prior to the full opening of the air exhaust valve 5. To facilitate the exhaust of the water from the fluid chamber 20 two or more openings 66 and 67 may afford communication with the pipe 23. The stem 12 is intended to fit rather nicely in the bore 68 of the web 14 through which it passes to prevent the pressure of the air at the instant of exhaust from exerting a back pressure upon the diaphragm 18 and to avoid any interference with the freedom of movement of the diaphragm 18, one or more holes 69, of sufficient size to permit free movement of water therethrough, may be provided to afford communication between the chamber 70 and the water in which the pump is submerged.
25 It will be observed that, with the parts 30 in the positions shown by the drawing, the pressures upon opposite sides of the diaphragm 43 are equal and that the compressed air is exhausted from the fluid chamber 45 of the fluid pressure motor 44 at the same time that the compressed air is exhausted from the pump chamber 1.
35

What is claimed is:

1. In a pneumatic pump, the combination with a pump chamber provided with water inlet and outlet valves, an air admission valve and an air exhaust port, of an air exhaust valve located outside of said pump chamber to control said air exhaust port, means for keeping said air exhaust valve closed against the pressure in said pump

chamber, and a motor for opening said air exhaust valve.

2. In a pneumatic pump, the combination with a pump chamber provided with water inlet and outlet valves, an air admission valve and an air exhaust port, of an air exhaust valve located outside of said pump chamber to control said air exhaust port, a spring for keeping said air exhaust valve closed against the pressure in said pump chamber, and a fluid pressure motor for compressing said spring and opening said air exhaust valve.

3. In a pneumatic pump, the combination with a pump chamber provided with water inlet and outlet valves, an air admission valve and an air exhaust port, of an air exhaust valve located outside of said pump chamber to control said air exhaust port, a spring for keeping said air exhaust valve closed against the pressure in said pump chamber, toggle-joint members for holding said air exhaust valve open, and fluid pressure motors for compressing said spring and moving said toggle-joint members.

4. In a pneumatic pump, the combination with a pump chamber provided with water inlet and outlet valves, an air admission valve and an air exhaust port, of an air exhaust valve located outside of said pump chamber to control said air exhaust port, means for holding said air exhaust valve closed against the pressure in said pump chamber, and means to actuate said air exhaust valve and said air admission valve according to predetermined water levels in said pump chamber.

5. In a pneumatic pump, the combination with a pump chamber provided with water inlet and outlet valves, an air admission valve and an air exhaust port, of an air exhaust valve located outside of said pump chamber to control said air exhaust port, a bell-crank lever connected to the air exhaust valve and a stem, a spring for keeping said air exhaust valve closed against the pressure in the pump chamber, a fluid pressure motor for opening the air exhaust valve, a float in the pump chamber controlling the operation of said fluid pressure motor when the water in the pump chamber has been lowered to a predetermined level, toggle-joint members connected with the air exhaust valve for holding it open, a second fluid pressure motor for moving said toggle-joint members when the water level in the pump chamber has risen to a predetermined level to permit the air exhaust valve to be closed and to open the air admission valve.

6. In a pneumatic pump of the class described, a pump chamber, water inlet and outlet valves, air inlet and outlet valves, a fluid pressure motor connected to said air exhaust valve for operating the latter, means associated with said air exhaust valve

for unseating said air inlet valve upon each seating operation of the former, and independent means for seating said air admission valve.

5 7. In a pneumatic pump of the class described, a pump chamber, water inlet and outlet valves, air inlet and outlet valves, a fluid pressure motor connected to said air exhaust valve for operating the latter, a
10 stem carried by said air exhaust valve, and toggle joint members attached to said stem at one end and to a fixed pivot at the other, said air inlet valve being also provided with a stem, the latter being disposed for engagement and operation by said toggle members when said air exhaust valve is operated in one direction.

8. In a pneumatic pump of the class described, a pump chamber, water inlet and
20 outlet valves, air inlet and outlet valves, a fluid pressure motor connected to said air exhaust valve for operating the latter, a stem carried by said air exhaust valve, toggle joint members attached to said stem at one end and to a fixed pivot at the other, said air inlet valve being also provided with a stem, the latter being disposed for engagement and operation by said toggle members when said air exhaust valve is operated in one direction, said toggle members being moved out of engagement with said stem upon operation of said air exhaust valve in the opposite direction, and means for operating said air inlet valve in the reverse direction upon such disengagement.

9. In a pneumatic pump of the class described, a pump chamber, water inlet and outlet valves, air inlet and outlet valves, a fluid pressure motor connected to said air
40 exhaust valve for operating the latter, a stem carried by said air exhaust valve, toggle joint members attached to said stem at one end and to a fixed pivot at the other,

said air inlet valve being also provided with a stem, the latter being disposed for engagement and operation by said toggle members when said air exhaust valve is operated in one direction, means for operating said air inlet valve in the reverse direction upon such disengagement, and a second fluid motor for insuring breaking of the toggle joint in the proper direction upon each operation of said air exhaust valve in the direction first-named.

10. The combination with a pneumatic
55 pump of the class described having air inlet and exhaust valves, of a toggle jointed element attached to one of said valves and adapted to engage and operate the other upon a breaking of the joint in one direction, and means for operating the valve to which said element is attached.

11. The combination with a pneumatic pump of the class described having air inlet and exhaust valves, of a toggle jointed element attached to one of said valves and adapted to engage and operate the other upon a breaking of the joint in one direction, means for operating the valve to which said element is attached, and means cooperating with said element for insuring proper breaking of said joint upon operation of said valve.

12. In a pneumatic pump of the class described, a pump chamber, water inlet and
75 outlet valves, air inlet and outlet valves, a fluid pressure motor connected to said air exhaust valve for operating the latter, and a toggle jointed element associated with said air exhaust valve and adapted when the
80 joint is broken in one direction to engage and operate said air inlet valve.

In witness whereof I hereto affix my signature.

HOMER S. ROGERS.
